ACIDS OF THE CYCLOPENTANO POLYHYDRO PHENANTHRENE SERIES AND THEIR DERIVATIVES AND A METHOD OF PRODUCING THE SAME

Hans-Georg Allardt, Philippsthal, and Lothar Strassberger, Berlin-Wilmersdorf, Germany, assignors, by mesne assignments, to Schering Corporation, Bloomfield, N. J., a corporation of New Jersey

No Drawing. Application October 20, 1936, Serial No. 106,564. In Germany October 24, 1935

31 Claims. (Cl. 260—397.1)

This invention relates to acids of the cyclopentano polyhydro phenanthrene series and their derivatives, particularly to hydroxy acids and unsaturated acids of the cyclopentano polyhydro phenanthrene series and their derivatives, and a method of producing the same.

It is known that ketones of the hydroaromatic series such as cyclohexanone or cyclopentanone can be converted with halogen aliphatic acid esters in the presence of metals, suitably zinc or magnesium, into the corresponding hydroaromatic hydroxy aliphatic acid esters; these hydroxy aliphatic acid esters, on saponification with alkaline agents yield the free hydroaromatic hydroxy aliphatic acids, on saponification with acid agents, however, by splitting of water under suitable reaction conditions the corresponding exo- or endocyclic unsaturated hydroaromatic aliphatic acids can be obtained.

In accordance with the present invention, this reaction, known as the Reformatsky reaction, can also be applied to ketones of the cyclopentano polyhydro phenanthrene series whereby hitherto unknown valuable compounds are obtained.

To the ketones of the cyclopentano polyhydro phenanthrene series which may serve as starting materials for the process of the present invention belong a number of ketones with hormone-like actions such as the follicle hormone of the formula $C_{18}H_{22}O_2$, the male sex hormone androsterone of the formula $C_{19}H_{30}O_2$, and other similar substances including androstenolone, cholestenone and so on and derivatives thereof wherein the hydroxyl group is replaced by a group convertible into the hydroxyl group.

The reaction of the halogen aliphatic acid esters on the ketones of the cyclopentano polyhydro phenanthrene series in the presence of metals suitably zinc or magnesium may take place in the usual manner as it is described, for instance, in Houben-Weyl, Methods of the Organic Chemistry, vol. 3, 3d edition, Leipzig 1930, page 96 seq. and 897 seq. The hydrolysis of the esters of the acids formed may likewise be carried out in the manner customary for hydrolysing an ester as it is described, for instance, in Houben-Weyl, Methods of the Organic Chemistry, vol. 2, 3d edition, Leipzig 1930, page 677 seq.

The acids of the cyclopentano polyhydro phenanthrene series or their derivatives obtained by the process of the present invention, i. e. the cyclopentano polyhydro phenanthreno hydroxy acids or the corresponding unsaturated cyclopentano polyhydro phenanthreno acids or their derivatives are valuable products as they are either themselves physiologically active or can be transformed into physiologically active substances; moreover the acids obtained by the process of the present invention have the particular advantage of being more or less water soluble.

The following examples serve to illustrate the present invention without, however, limiting the same to them.

Example 1

1.1 parts of androstenolone-acetate-3, 1 part of ethyl bromo-acetate and 0.3 part of zinc wool are heated to boiling in 10 parts of dry benzene until the reaction is complete. This is recognized by the practically complete solution of the zinc. The reaction product is poured into dilute sulphuric acid, the benzene layer is separated, washed with sodium carbonate solution and dried. On careful evaporation of the benzene solution the ester of the 3,17'-dihydroxy-androstenyl-17''-acetic acid is obtained which on alkaline saponification according to customary methods yields the free acid, crystallising from alcohol in colorless needles of M. P. 220° with decomposition.

Example 2

In a similar manner to that of Example 1, 3.3 parts of androstenolone-acetate-3 are treated in dry benzene with 3.7 parts of α -bromo-propionic-acid-ethyl-ester with the addition of 0.7 part of zinc wool; on working up the ester of the 3,17'-dihydroxy-androstenyl-17''-propionic acid is obtained and by alkaline saponification the free acid of M. P. 230° with decomposition.

Of course, various modifications in the procedure of the process of the present invention may be resorted to within the scope of the appended claims without departing from the principles set forth herein. Thus, for instance, instead of the halogen aliphatic acid esters mentioned also other halogen aliphatic acid esters

may be used for reacting with the ketones of the cyclopentano polyhydro phenanthrene series.

What we claim is:

1. In a method of producing acids of the cyclopentano polyhydro phenanthrene series and their derivatives, the step which comprises reacting a 13-methyl cyclopentano polyhydro phenanthrene having a keto group in one of the 3 and 17 positions with a halogen-substituted lower aliphatic monocarboxylic acid ester in the presence of a metal capable of taking part in a Reformatsky type of reaction.

2. A method according to claim 1, wherein the condensing reaction takes place in the presence of a metal of the second group of the periodic system.

3. A method according to claim 1, wherein hydrolysis of the acid esters formed is carried out with an alkaline agent.

4. A method according to claim 1, wherein hydrolysis of the acid esters formed is carried out with an acid agent.

5. A method according to claim 1, wherein the other of the 3 and 17 positions is occupied by a group that on hydrolysis can be replaced by a hydroxyl group.

6. A method according to claim 1, wherein androstenol-3-one-17 is used as starting material.

7. A method according to claim 1, wherein a 17-keto compound is employed as starting material which has in the 3-position a substituent which on hydrolysis can be replaced by an OH group.

8. A method of producing acids of the cyclopentano polyhydro phenanthrene series and their derivatives, comprising reacting a 13-methyl cyclopentano polyhydro phenanthrene having a keto group in one of the 3 and 17 positions with a halogen-propionic acid ester in the presence of a metal capable of taking part in a Reformatsky type of reaction.

9. A method of producing acids of the cyclopentano polyhydro phenanthrene series and their derivatives, comprising reacting a 13-methyl cyclopentano polyhydro phenanthrene having a keto group in one of the 3 and 17 positions, with a bromo-propionic acid ester in the presence of a metal capable of taking part in a Reformatsky type of reaction.

10. A method according to claim 8, wherein the cyclopentano polyhydro phenanthrene compound is androstenol-3-one-17.

11. A method according to claim 8, wherein the cyclopentano polyhydro phenanthrene compound is a 17-keto compound having a substituent in the 3-position which on hydrolysis can be replaced by an OH group.

12. 3,17'-dihydroxy-androstenyl-17'' propionic acid of M. P. 220°.

13. A neutralization reaction product of 3,17'-dihydroxy-androstenyl-17'' propionic acid.

14. An ester of 3,17'-dihydroxy-androstenyl-17'' propionic acid.

15. A salt of 3,17'-dihydroxy-androstenyl-17'' propionic acid.

16. The product of the condensation of a compound of the 13-methyl and 10,13-dimethyl cyclopentano polyhydro phenanthrene series having a keto group occupying one of the 3 and 17 positions, with a halogen-substituted lower aliphatic mono-carboxylic acid ester.

17. The unsaturated product of the condensation of a compound of the 13-methyl and 10,13-dimethyl cyclopentano polyhydro phenanthrene

series having a keto group occupying one of the 3 and 17 positions, with a halogen-substituted lower aliphatic mono-carboxylic acid ester with elimination of the elements of water.

5 18. A compound of the nuclearly saturated and nuclearly unsaturated cyclopentano polyhydro phenanthrene series of the structure

wherein R indicates the radical C_nH_{2n} , n being a whole number, R' is a member of the group consisting of H, alkali metals and hydrocarbon radicals, X is a member of the group consisting of OH and radicals which are replaced on hydrolysis by the OH group, and Y is a member of the group consisting of H and CH_3 .

25 19. A compound of the nuclearly saturated and nuclearly unsaturated cyclopentano polyhydro phenanthrene series of the structure

wherein R indicates the radical C_nH_{2n} , n being a whole number, R' is a member of the group consisting of H, alkali metals and hydrocarbon radicals, X is a member of the group consisting of OH and radicals which are replaced on hydrolysis by an OH group, and Y is a member of the group consisting of H and CH_3 .

45 20. Acids of 13-methyl cyclopentano polyhydro phenanthrenes having a

50 group in one of the 3 and 17-positions, R being a lower monocarboxylic aliphatic acid radical and n a whole number.

55 21. The neutralization reaction products of the acids defined in claim 20.

22. The esters of the acids defined in claim 20.

23. The salts of the acids defined in claim 20.

24. A method according to claim 1 including the step of hydrolyzing the acid ester formed.

60 25. A method according to claim 8 including the step of hydrolyzing the acid ester formed.

26. A method according to claim 9 including the step of hydrolyzing the acid ester formed.

27. The method of producing acids of the 10,13-dimethyl cyclopentano polyhydro phenanthrene series and their derivatives, comprising reacting a member of the group consisting of androstenolones and androstenolone derivatives wherein the hydroxy group has been replaced by a group which can in turn be replaced by the hydroxy group with the aid of hydrolysis, with an alpha-halogeno-propionic acid ester.

28. The method of producing acids of the 10,13-dimethyl cyclopentano polyhydro phenan-

threne series and their derivatives, comprising reacting androstenol-3-one-17 and its derivatives wherein the hydroxy group has been replaced by a group which can in turn be replaced by the hydroxy group with the aid of hydrolysis, with an alpha-halogeno-propionic acid ester capable of replacing the ketonic oxygen with the propionic acid ester radical.

29. A compound of the class consisting (1) of the nuclearly saturated and nuclearly unsaturated cyclopentano polyhydro phenanthrene series of the structure

wherein

occupies one of the 3- and 17-positions and

5 the other, R indicating the radical C_nH_{2n} , n being a whole number, R' is a member of the group consisting of H, alkali metals and hydrocarbon radicals, X is a member of the group consisting of OH and radicals which can be replaced by OH with the aid of hydrolysis, and Y is a member of the group consisting of H and CH_3 ; and 10 (2) the degradation products of the aforementioned compounds wherein the

15 group is replaced by $=CH.R.COOR'$.

20 30. Alkyl esters of the acids defined in claim 20.

31. An alkyl ester of 3,17'-dihydroxy-androstenyl-17''-propionic acid.

HANS-GEORG ALLARDT.
LOTHAR STRASSBERGER.
